TYPOGRAPHICAL CASTING MACHINE

Paul Hilpman, Garden City, N. Y., assignor to Mergenthaler Linotype Company, a corporation of New York

Application August 11, 1950, Serial No. 178,829

2 Claims. (Cl. 199—50)

This invention relates to quadding and centering devices for typographical casting machines and more particularly to devices of the type disclosed in the Frolander Patent No. 1,971,400, the Hilpman Patent No. 2,255,254, and the Krusberger application Serial No. 116,700, filed September 20, 1949, now U. S. Patent No. 2,642,180. The Krusberger application is directed to the latest improvements embodied in the commercial devices.

In these quadding and centering devices, the jaws are moved into contact with the composed line by a vertically movable rod which is locked in its downwardly moved position by means of a series of detents actuated by the melting pot as it is swung into casting position. After casting, the locking detents are released by the upward movement of the first elevator and the jaws then restored to their original positions of maximum separation by the vertically movable rod. This rod is operated by two different cams on the main shaft, one of which effects the jaw closing and opening movements, and the other of which applies a supplemental pressure to the jaws to urge them inwardly from their line contacting positions to squeeze the line tight enough to insure the straightening and complete sidewise contact of all matrices composed therein as well as to straighten up the jaws so that their matrix engaging faces make complete contact with the side faces of the end matrices.

The present invention presents two additional improvements upon prior devices: According to one, the line squeezing pressure is maintained for a longer period than before in order to avoid any endwise shifting of the composed line with reference to the slug after the casting operation, and according to the other, the line squeezing pressure, instead of being released abruptly as before, is released momentarily before being released in order to maintain the jaws in wiping contact with the end matrices as the composed line is lifted from between the jaws. These improvements will best be understood from the detailed description which follows.

Referring to the drawings:

Fig. 1 is a side elevation of the jaw operating mechanism, showing the two cams in inactive positions;

Fig. 2 is a similar view but showing the cams in action;

Fig. 3 is a front view of the jaws, the vertically movable rod, and the locking detents during a quadding operation with the right-hand jaw;

Fig. 4 is a detail view, on a greatly enlarged scale, of the line squeeze mechanism as modified according to the present invention;

Fig. 5 is a detail front view of the locking detents under line squeeze pressure;

Fig. 6 is a detail side view of the parts shown in Fig. 5; and

Fig. 7 is a view similar to Fig. 3 but showing the line being lifted from between the jaws under relaxed (but not released) line squeeze pressure.

The matrices 1 are composed in line in an assembler in the usual way and transferred to a vertically movable transporter or first elevator 3, which thereupon descends to position the line between the left-hand jaw 4 and the right-hand jaw 5 (see Figs. 3 and 7) and in front of a slotted mold (not shown). The mold then advances from the rear into contact with the composed line and with the two jaws preparatory to the slug casting operation. Thereafter, the mouthpiece of the melting pot (not shown) is advanced from the rear into contact with the rear face of the mold and molten metal then injected into the mold for the casting of the slug against the composed line.

2

After the slug has been cast, the melting pot is moved rearwardly out of contact with the mold and the latter likewise moved rearwardly out of contact with the composed line, whereupon the mold is carried around from its horizontal casting position to a vertical ejecting position, the first elevator in the meantime being raised to deliver the composed line to the matrix distributing devices and finally coming to rest in its original or line receiving position.

10 As more fully shown and described in the Frolander patent above referred to, the two jaws 4 and 5 are mounted for movement in the vise frame in the customary manner, being carried by supporting blocks slideable in suitable guideways formed in the vise frame, and are movable toward and from each other by a periodically operated part in the form of a vertically movable rod 11 which may be connected at its upper end to the respective jaws through the medium of two small but oppositely disposed bell crank levers 12 and 13 pivoted at 14 and 15 to the vise frame, the longer arms of said levers being connected by short links 16 and 17 to the supporting blocks for the respective jaws, and the shorter arms of said levers being arranged for connection to or disconnection from the rod 11. According to this arrangement, 15 when the rod 11 is moved downwardly from its uppermost position (which is its normal position of rest), it will move the two jaws equidistantly toward each other (assuming both to be connected to the rod) until they contact with the opposite ends of the composed line which 20 has previously been positioned between them, and when the rod is moved upwardly for restoration to its position of rest, it will in like manner move the jaws equidistantly away from each other to return them to their original positions of maximum separation. Since the composed 25 lines positioned between the jaws may vary in length, the actual extent of movement of the rod 11 will of course vary accordingly and hence provision is made for such varied movement of the rod in its actuating connections 30 in the usual way.

40 As also more fully shown and described in the Frolander patent, a suitable device in the nature of a segmental grooved member 18 is provided at the upper end of the rod 11 for connecting the jaws thereto, this grooved member being adjustable by a handle 19 through a rack and 45 pinion arrangement 20 so as selectively to connect either or both of the jaws to the rod as desired for quadding at either end of the line, or for centering, or for regular machine operation. The handle 19 and the actuating connections thus constitute means for conditioning the 50 machine for a quadding or regular machine operation, as may be desired.

The rod 11 is slideable in upper and lower bearings in the vise frame and is operated through a train of connections, indicated generally by the reference numeral 55 26, from an edge cam B fast to the main shaft A of the machine. This cam B, which makes one complete rotation at each cycle of operation of the machine, acts to move the rod first downwardly to effect the inward or closing movement of the jaws and then upwardly to effect 60 the outward or separating movement of the jaws.

A locking device is provided to hold the rod 11 in its downwardly moved position during a quadding or centering operation. The locking device herein shown is the same as the improved type of device fully illustrated and 65 described in the Krusberger application above referred to, comprising a plurality of pawls or detents disposed horizontally one upon another in vertical stack formation and enclosed within a box or cage 41. The detents are each formed at their rear ends with a series of uniformly spaced 70 rack teeth for engagement with similar but oppositely disposed rack teeth 42 formed directly in the rod 11. The teeth 42 extend practically throughout the length of the rod 11 or, in any event, for a distance equal to the full extent of movement of the rod for quadding or centering.

75 Normally, or when the locking mechanism is inactive, the cage 41 is held in a forward position, with all the detents in alignment and with their teeth clear of the teeth on the rod 11. However, when the locking mechanism is operated, the cage 41 is pushed rearwardly to 80 engage one or another of the detents with the rod 11, that particular detent being the one whose teeth will

3

accurately mesh with the rack teeth on the rod and the others (whose teeth do not so mesh) being permitted to yield with reference to the cage.

The cage 41 is mounted for such backward and forward movements in a housing 43 which contains the upper bearing 25 for the rod 11. At its forward end, the housing 43 is provided with a fixed nut (not shown) into which is threaded a short rotatable screw (not shown) having a swivel connection to the cage 41. When the screw is rotated in one direction the cage 41 will be forced rearwardly to engage the detents with the rod 11, whereas when the screw is rotated in the opposite direction the cage will be drawn forwardly to disengage the detents from the rod.

As fully shown and described in the Krusberger application, the locking mechanism, instead of being operated by the jaw moving mechanism (as in the Frolander and Hilpman patents mentioned), is operated by independent mechanism which includes two sets of connections, one set actuated by the melting pot as it is swung into casting position and which effects the locking action before casting, and the other set actuated by the first elevator as it is moved upwardly from casting position and which effects the unlocking action after casting.

Both sets of connections include a double-armed lever 50 pinned to the forward end of the above-mentioned screw. At one end, the lever 50 is connected to a vertical link 51, which forms part of the pot-actuated connections, and at its opposite end, it is formed with a cam plate 70 which is arranged to be engaged and actuated by a finger 75 carried by the first elevator. After casting, when the first elevator moves upwardly to lift the composed line from between the jaws for distribution, the finger 75, by its engagement with the cam plate 70, will effect the disengagement of the locking detents from the vertically movable rod. This action is timed to take place before the composed line has moved entirely clear of the clamping jaws (see Fig. 7), the purpose being to delay the disengagement of the locking detents from the rod until after the latter, in the manner presently to be described, is allowed to rise slightly in relaxing the pressure of the jaws on the composed line.

As in the Krusberger application, the locking detent cage 41 is mounted in the bushing 43 not only for a rearward and forward movement, as above described, but also for a limited vertical or upward and downward movement with reference thereto. Normally, the cage 41 is held in its upward position within the housing by a spring-actuated plunger (not shown) enclosed within the housing 43. The downward movement of the cage is effected after the detents have been engaged with the vertically movable rod 11 and consequently is imparted to said rod in order to force the clamping jaws inward from their line contacting positions to squeeze the line before the casting operation. The mechanism employed for the purpose is substantially the same as that more fully shown and described in both the Krusberger application and the Hilpman patent, but since it is this mechanism with which the present invention is primarily concerned, it will be shown and described herein, comprising a fore-and-aft slide 90 having a pin and slot connection with the housing 43 at one side thereof. The rear end of the slide 90 is hook-shaped to cooperate with a hooked plate 92 carried by a spring-actuated link 93 controlled, through a pivoted lever 93^a, by a cam C on the main cam shaft A of the machine. At its forward end, the slide 90 is bent to provide a lip 94 arranged to engage in front of a cam arm 95 pivotally suspended from the free end of a lever 96 pivoted at 97 to the housing 43 at the side opposite that on which the slide 90 is located. The lever 96 overlies the housing 43 and is formed with a lug which passes through the top of the housing and bears upon the uppermost detent within the cage 41. The cam arm 95 engages a roller 98 mounted on a fixed pin between the housing and a strap 99 which holds the arm against sidewise movement.

According to this arrangement, when the slide 90 is moved rearwardly by the link 93 (which is actuated by a powerful spring), the lip 94 engages and rocks the cam arm 95 which, by its engagement with the roller 98, draws the lever 96 downwardly to apply the full downward pressure of the actuating connections to the locking detents and through them to the rod 11 (see Figs. 2, 3, 6 and 7). After the casting operation, and when the operating link

4

93 is restored to its original position under cam control, a spring exercises itself to draw the slide 90 forward and allow the cam arm 95 to rock back to its original position as the lever 96 is raised by the locking detents in response to the upward pressure of the spring plunger within the housing (see Fig. 1). It is this upward movement of the locking detents which releases the pressure on the composed line while they are still engaged with the rod 11 and before the first elevator lifts the line from between the clamping jaws.

Coming now to the present invention, it is first pointed out that the high concentric track C¹ of the cam C, as compared to prior arrangements, has been extended at its trailing end from the point x to the point x¹ in Fig. 4, which means that the full line squeeze pressure exerted on the rod 11 through the connections above described will be maintained for a longer period than before. This prolonged period has been fixed with reference to the time the mold is moved rearwardly out of contact with the composed line, that is to say, the extended portion of the cam track will cause the jaws to maintain full pressure on the line until after the mold has been backed off. In this way, there can be no endwise movement of the matrices with reference to the slug contained in the mold until after the type characters have been withdrawn from the matrix cavities. Heretofore, the high track of the cam has terminated at the point x, dropping off abruptly as indicated by the dotted line x² and releasing the line squeeze pressure before the retreat of the mold. As will be evident, any shifting of the matrices or space-bands in the composed line while the latter is still in contact with the cast slug will mar the type characters or even shear them off.

It is next pointed out that the cam track C¹, instead of dropping off abruptly as heretofore, has been further extended at its trailing end by the addition of a shoe D presenting a supplemental cam track C² which is joined to the main cam track by a short sloping surface C³. The depth of the supplemental cam track C² in relation to the main cam track C¹ is regulated so that, while the line squeeze pressure is relaxed, it is not completely released. The amount of relaxation is such that the jaws will not be allowed to back off out of contact with the end matrices in the composed line but, on the contrary, will still be held under a slightly relaxed pressure in contact with the end matrices, this action being timed to take place just before and for a short period after the first elevator has started on its upward movement to carry the line from between the jaws (see Fig. 7). In this way, the jaws and the end matrices are maintained in wiping contact to dislodge any adhering type metal.

As the cam follower 93^b (on the lever 93^a) runs off the supplemental cam track C², it travels along a gradual sloping surface C⁴, allowing the line squeeze pressure to be gradually relaxed but not completely released until after the composed line has been carried upwardly beyond the jaws. Hence, any sudden expansion of the line (due for instance to bent matrices) will be taken care of while the jaws are still locked against separation. Once the cam follower 93^b passes beyond the surface C⁴, the locking detents will be released by the finger 75 (see again Fig. 7) and the rod 11 then raised in the usual way to restore the jaws to their original position of maximum separation.

As shown in Fig. 4, the shoe D is radially adjustable on the cam C in order to vary the amount of relaxation of pressure, as controlled by the supplemental cam track C², to meet different conditions. To this end, the shoe is formed with an elongated slot D¹ through which passes a clamping screw D². The length of the slot D¹ will control the extent of the radial adjustment of the shoe. A compression spring D³, housed within the shoe, tends to push the shoe radially outward. The spring is confined within the recess by the head of a bolt D⁴ which is adjustable to vary the tension of the spring.

It is obvious that, if no adjustment were desired, the supplemental cam track C² could be formed integral with the cam C.

The invention has been shown in preferred form and by way of example, and many modifications and adaptations will readily occur to those skilled in the art without departing from the spirit of the instant disclosure. It should be understood, therefore, that the invention is not

limited to any specific form or embodiment except insofar as such limitations are specified in the appended claims.

What is claimed is:

1. In a typographical casting machine wherein the composed line is carried to and from casting position by a vertically movable transporter, the combination of a pair of line clamping jaws movable one toward the other in quadding, mechanism for effecting such quadding movement of the jaw, and additional spring-powered mechanism to urge the jaw inwardly from its line contacting position to squeeze the line before casting and to release the line after casting independently of the jaw moving mechanism, said additional mechanism including a rotary cam mounted on the main drive shaft of the machine and a cam follower tracking on said cam, characterized in that the cam track is extended and slightly depressed at its trailing end to relax but still maintain the

line squeezing spring pressure through the cam follower before said pressure is completely released during the initial upward movement of the transporter in lifting the line from between the jaws.

2. A combination according to claim 1, wherein the depressed cam track extension is formed on a shoe which is adjustable to vary the extent of the depression.
